(57) **CLAIM**

The ornamental design for a drug injection device for patient, as shown and described.

DESCRIPTION

1. Drug injection device for patient

1.1 is a top perspective view of a drug injection device for patient;

1.2 is a front view thereof;

1.3 is a rear view thereof;

1.4 is a top view thereof;

1.5 is a bottom view thereof;

1.6 is a right side view thereof;

1.7 is a left side view thereof.

The broken lines in the drawing depict unclaimed portions of the drug injection device for patient only and form no part of the claimed design.
